UNITED STATES PATENT OFFICE.

JOHN H. STEINMETZ, OF CHICAGO, ILLINOIS.

ADJUSTABLE STOOL.

1,116,947.

Specification of Letters Patent. Patented Nov. 10, 1914.

Application filed April 28, 1913. Serial No. 763,980.

To all whom it may concern:

Be it known that I, JOHN H. STEINMETZ, a citizen of the United States, residing at Chicago, in the county of Cook and State 5 of Illinois, have invented certain new and useful Improvements in Adjustable Stools, of which the following is a specification.

This invention relates in general to stools, but has more particular reference to stools 10 of the type commonly known as music stools or piano stools, and aims to provide a stool of this character which shall be so constructed that the seat may be tilted or inclined to suit the convenience of the user.

15 For certain classes of musical instruments, such, for example, as pianos and organs, in which the finger keys are used, a stool having a horizontal seat is preferable and is almost universally employed. For other classes of 20 musical instruments, particularly the mechanical class, such as piano players and pipe organs, which require considerable force to operate the pedals, it is essential that the stool or bench be inclined toward 25 the instrument so as to throw the weight of the player into the action of the feet. In order to obviate the expense and inconvenience of having two seats of this character for the different uses to which they may be put in 30 the same household or music-room, it has been proposed to make the seats of piano stools and benches adjustable from a horizontal to an inclined position.

35 My present invention has reference more particularly to a stool of this latter type and has for its primary object the provision of an improved means of adjustment, whereby the seat may be adjusted so that the stool may be used with the seat in either horizontal or inclined position, the adjusting 40 means being so constructed that the seat may be readily converted or adjusted from one position to another and be securely supported in both positions on the stool base.

45 Other objects of the invention will be apparent as the same becomes better understood by reference to the following description when considered in connection with the accompanying drawings.

50 Referring to the drawings: Figure 1 is an elevation of a stool embodying my invention; Fig. 2 is an enlarged fragmentary view of my improved seat adjusting means; and Fig. 3 is a longitudinal sectional view taken 55 substantially on the line of 3, 3 of Fig. 2.

On the drawings reference character 5

designates generally the base of the stool, which may be of any preferred shape or construction. The center post 6 being interiorly threaded in the usual manner to receive a 60 threaded supporting post 7. This construction is customary in piano stools and other stools of this general character and permits a vertical adjustment of the post to position the seat at any height convenient to the 65 user. In the present instance the post 7 is flattened on opposite sides above the threaded portion, as indicated by reference character 8, and is provided at its upper end with a longitudinally projecting bearing stud 9. 70 The seat 11, which may be of any well-known or preferred construction, has attached to its bottom, by means of screws 12 or other suitable fastening means, a pair of bracket members 13, preferably of angle 75 shape, as best shown in Fig. 3. These members are positioned so that the depending portions thereof are disposed contiguously to the flat faces 8 of the supporting post and each is provided with, near its lower end, an 80 elongated slot 14 to receive the ends of a pin or stud 15 projecting laterally from the supporting post. In practice the ends of this pin or stud are riveted or headed to permanently but slidingly and pivotally 85 connect the bracket members to the post.

For the purpose of supporting the seat in adjusted positions on the post I have provided the bracket members 13 with a plurality of sockets in which the stud 9 is adapted to seat. In the present instance the 90 sockets 16 are formed in bars or plates 17 disposed between the angle members and secured thereto by rivets 18. For convenience in manufacture I prefer to employ two 95 socket bars placed side by side but it will be obvious that the socket member may be formed in one piece or may, if preferred, be made integral with either or both of the bracket members.

When the stud 9 is seated in the center one 100 of the sockets the seat is supported by the stud in substantially horizontal position, as shown in Fig. 2, the seat being prevented from tilting by the pin and slot connection 105 14, 15 between the bracket members and the post 7. When it is desired to adjust the seat to tilted position the seat may be raised sufficiently to disengage the stud 9 from the socket and then tilted in either direction 110 about the pin 15 as a pivotal center whereupon the seat may be lowered to engage the

stud in one of the lateral sockets. The seat will thereupon assume the position indicated by dotted lines in Fig. 1.

It will be manifest from the foregoing that I have provided a stool, the seat of which may be readily converted from a horizontal to an inclined position by simply lifting the seat and tilting it to the required position, whereupon the engagement of the 10 stud 9 in a socket will maintain the seat in its adjusted position and stably support the same. My improved stool is, therefore, capable of use either as an ordinary piano stool, with the seat in horizontal position, or as a 15 stool for use in connection with mechanical players, the conversion of the stool from one position to another being readily effected.

While I have shown and described a preferred form of my invention, it will be obvious that the details of construction disclosed are capable of considerable modification and variation without departure from the essence of the invention or sacrificing any of the material advantages thereof.

I claim:

An adjustable stool comprising a base, a post rising from the base and provided at its upper end with an upright laterally enlarged head, the upper portion of the head tapering upwardly to a centrally disposed 30 upstanding lug, said head being provided with transversely alined projections below and in vertical alinement with the lug, a seat, a pair of bracket members depending from the seat and embracing the head of the 35 post, said bracket members being provided with longitudinal slots receiving the respective projections, and a socket member located between the bracket members and provided with a series of sockets for individual engagement with the lug and arranged on an arc struck from the axis of the projections on the head, substantially as shown and described.

JOHN H. STEINMETZ.
